The ornamental design for a multimedia computer satellite speaker, as shown and described.

DESCRIPTION

FIG. 1 is an isometric view of a multimedia computer satellite speaker showing our new design;

FIG. 2 is a top plan view thereof;

FIG. 3 is a bottom plan view thereof;

FIG. 4 is front elevational view thereof;

FIG. 5 is rear elevational view thereof;

FIG. 6 is a left side elevational view thereof;

FIG. 7 is a right side elevational view thereof;

FIG. 8 is a sectional top view thereof, taken along the lines 8—8 in FIG. 6;

FIG. 9 is a sectional top view thereof, taken along the lines 9—9 in FIG. 6;

FIG. 10 is a sectional top view thereof, taken along the lines 10—10 in FIG. 6;

FIG. 11 is an isometric front view of a second embodiment of the multimedia computer satellite speaker of FIG. 1;

FIG. 12 is a top plan view of FIG. 11;

FIG. 13 is a bottom plan view of FIG. 11;

FIG. 14 is front elevational view of FIG. 11;

FIG. 15 is rear elevational view of FIG. 11;

FIG. 16 is a left side elevational view of FIG. 11;

FIG. 17 is a right side elevational view of FIG. 11;

FIG. 18 is a sectional top view thereof, taken along the lines 18—18 in FIG. 16;

FIG. 19 is a sectional top view thereof, taken along the lines 19—19 in FIG. 16; and,

FIG. 20 is a sectional top view thereof, taken along the lines 20—20 in FIG. 16.

The broken lines showing control knobs, cable jacks, and assembly screw holes are for illustrative purposes only and form no part of the claims invention.

The broken lines bounding interiors of sectional top views define the bounds of the claimed design.
